(57) **CLAIM**

The ornamental design for a beverage container, as shown and described.

DESCRIPTION

FIG. 1 is a perspective view of a beverage container showing my new design in accordance with a first embodiment of the invention;

FIG. 2 is a front elevational view thereof;

FIG. 3 is a rear elevational view thereof;

FIG. 4 is a right side elevational view thereof, the left side being a mirror image thereof;

FIG. 5 is a top elevational view thereof;

FIG. 6 is a bottom elevational view thereof;

FIG. 7 is a perspective view of a beverage container showing my new design in accordance with a second embodiment of the invention;

FIG. 8 is a front elevational view thereof;

FIG. 9 is a rear elevational view thereof;

FIG. 10 is a right side elevational view thereof, the left side being a mirror image thereof;

FIG. 11 is a top elevational view thereof;

FIG. 12 is a bottom elevational view thereof;

FIG. 13 is a perspective view of a beverage container showing my new design in accordance with a third embodiment of the invention;

FIG. 14 is a front elevational view thereof;

FIG. 15 is a rear elevational view thereof;

FIG. 16 is a right side elevational view thereof, the left side being a mirror image thereof;

FIG. 17 is a top elevational view thereof;

FIG. 18 is a bottom elevational view thereof;

FIG. 19 is a perspective view of a beverage container showing my new design in accordance with a fourth embodiment of the invention;

FIG. 20 is a front elevational view thereof;

FIG. 21 is a rear elevational view thereof;

FIG. 22 is a right side elevational view thereof, the left side being a mirror image thereof;

FIG. 23 is a top elevational view thereof; and,

FIG. 24 is a bottom elevational view thereof.

The broken lines shown in the drawings form no part of the claimed design.
